UNITED STATES PATENT OFFICE.

CARL E. CARLSON AND ALBERT C. GRUNWALD, OF CHICAGO, ILLINOIS, ASSIGNEES TO PRECISION METAL WORKERS, OF CHICAGO, ILLINOIS, A CORPORATION OF ILLINOIS.

DESIGN FOR A FLOWERPOT.

Application filed March 29, 1928. Serial No. 26,073. Term of patent 14 years.

To all whom it may concern:

Be it known that we, CARL E. CARLSON and ALBERT C. GRUNWALD, citizens of the United States, residing at Chicago, in the county of Cook and State of Illinois, have invented a new, original, and ornamental Design for a Flowerpot, of which the following is a specification, reference being had to the accompanying drawing, forming part thereof.

Figure 1 is an elevational view of a flowerpot showing our new design.

Figure 2 is a bottom plan view thereof.
We claim:

The ornamental design for a flowerpot as shown.

In witness whereof, we hereunto subscribe our names this 24th day of March, 1928.

CARL E. CARLSON.
ALBERT C. GRUNWALD.
